KNITTING MACHINE

Eugene M. Zesch, Shillington, Pa., assignor to
 Rosedale Knitting Company, Laureldale, Pa.,
 and Karl Lieberknecht, Inc., Reading, Pa., both
 corporations of Pennsylvania

Application November 6, 1948, Serial No. 58,674

14 Claims. (Cl. 66—89)

1

This invention relates to knitting machines. More specifically, it is concerned with straight knitting machines of the type disclosed in U. S. Patent #2,432,108, granted to me on December 9, 1947, and designed for the production of full fashioned stocking blanks with diagonally sutured narrowed and widened heel cheeks which latter are formed from separate yarns upon end groups of needles while the intermediate or instep needles of a series are idled, the heel needles being gradually reduced in number at predetermined variant intervals during the knitting of the upper segments or gores of the heel cheeks and gradually increased in number at regularly recurrent intervals during the knitting of the lower heel segments or gores, by blade-like selectors which are first progressively shifted outward away from each other and afterwards shifted progressively toward each other. The heel cheeks thus formed on the patented machine are square in configuration and characterized by miter sutures.

The chief aim of my present invention is to make it possible to produce, on a machine of the above type, flat stocking blanks such as featured in U. S. Patent #2,435,489, granted to E. B. Beacham on February 3, 1948, having vertically oblong heel cheeks which result from narrowing at predetermined intervals during the formation of the upper segments or gores and widening at different intervals during the formation of the lower segments or gores. With this objective view, I have devised, as more fully set forth hereinafter, improved modified mechanisms for shifting the selectors and for correspondingly shifting the heel yarn carrier stops, as well as improved means for controlling these mechanisms in the manner necessary to determine the formation of the oblong heel cheeks of the Beacham stockings.

Other objects and attendant advantages will appear from the following detailed description of the attached drawings, wherein

Fig. 1 is a fragmentary view, in front elevation, of a straight stocking knitting machine conveniently embodying my present invention.

Fig. 2 is a fragmentary view of the machine in top plan drawn to a somewhat larger scale and showing more particularly the improved mechanism provided for shifting the selector blades.

Fig. 3 is a fragmentary view in cross section taken as indicated by the angled arrows III—III in Figs. 1 and 2.

Fig. 4 is a view in end elevation looking as indicated by the angled arrows IV—IV in Fig. 1.

2

Fig. 5 is a fragmentary view in cross section on a larger scale and taken as indicated by the angled arrows V—V in Fig. 2.

Fig. 6 is a view like Fig. 4 with certain of the parts differently positioned.

Fig. 7 is a broken out fragmentary view in front elevation corresponding to Fig. 1 showing the means by which the shifting mechanisms for the selector blades and for the heel yarn carrier stops of machine are controlled during the heel knitting.

Fig. 8 is a cross section taken as indicated by the angled arrows VIII—VIII in Fig. 7.

Fig. 9 is a fragmentary view in plan looking as indicated by the angled arrows IX—IX in Fig. 7.

Fig. 10 is a detail cross section taken as indicated by the angled arrows X—X in Fig. 1 showing the means provided for automatically introducing the stops by which the inward traverse of the heel yarn carriers is limited during the heel knitting.

Fig. 11 is a fragmentary view in plan of the parts shown in Fig. 10.

Fig. 12 shows the foot portion of a stocking blank with oblong heel cheeks produced by my improved machine.

Fig. 13 is a spread out diagrammatic view showing the interlooping along the diagonal suture of one of the heel cheeks of the blank in Fig. 12, and

Figs. 14—22 are diagrammatic views showing successive positions to which the selector blades and the yarn carriers are moved relative to the needles during the formation of the heel cheeks of the stockings.

As in my prior patent, selector blades indicated at 15 and 16 and provided for action upon end groups of the needles N employed in each section of the machine for the heel knitting, are

40 secured to collars 18 and 19 so as to be rockable about and shiftable along a horizontal rod 20 with their free ends resting on the needle bar

21 as shown in Fig. 3. The rod 20 is fixed in the swinging ends of a plurality of upright arms 22

45 on horizontal rock shaft 23 which is rotatably supported in bearing brackets 24 bolted to the upper front rail or bed 25 of the machine framework.

The shaft 23 is arranged to be oscillated through a pendent arm 26 (Figs. 1 and 3) having

50 a roller 27 thereon which, during the heel knitting, is shifted into the path of a rotary cam

28 on the cam shaft 29 of the machine by a fork

30 under control of mechanism which may be like that disclosed in my prior patent supra.

Rotative movement of the rock shaft 23 in one direction is limited by engagement of a stop fin-

ger 31 thereon with a fixed bar or rod 32 of the machine, its movement in the opposite direction being yieldingly opposed by a draw spring 33 tensioned between said finger and a fixed anchorage 34 on the lower back rail 35 of the machine framework. Also as in my patent supra, the collars 18 and 19 are engaged by clevised lugs 36 and 37 respectively affixed to longitudinally shiftable slide bars 38 and 39 which are disposed, one above the other, and which are guided for endwise movement in the end brackets 24. The separate yarns used in the heel knitting are fed by carriers 40 and 41 respectively pendent from two of the usual horizontal carrier bars 42 and 43 of the machine.

The improved mechanism which I have devised for shifting the slide bars 38 and 39 whereto the selector blades 15 and 16 are attached, includes a pair of axially-aligned right and left hand screw spindles 45 and 46 which are rotatively supported in spaced bearings 47, 48 and 49 bolted to the rail or bed 25 at one end of the machine. Associated with the spindles 45 and 46 are follower nuts 50 and 51 having projections 50a and 51a which are engaged from opposite sides by set screws 52 and 53 (Fig. 2) adiustable in lugs 54 and 55 on the slide bars 38 and 39. Mounted side by side on the inner ends of the spindles 45 and 46 adjacent the central bearing 48, are forward and reverse ratchet wheels 56, 57 and 58, 59 respectively, arranged to be nicked at different times by pawls 60, 61 and 62, 63, see Figs. 4, 5, and 6. The pawls 60, 61 and 62, 63 are drawn toward each other by springs 64 and 65 and pivoted for independent movement on studs 66 and 67 projecting laterally from the inner ends of slides 68 and 69. As shown, the slides 68 and 69 are constrained to reciprocatory movement transversely of the machine in a guide block 70 affixed to an end projection of the center bed 71 of the machine. Overthrow of the spindles 45 and 46 is prevented by action of spring detents 72, 73 upon stop disks 74 and 75 respectively, which have peripheral notches corresponding in number to the teeth of the individual ratchets 56—59. The slides 68 and 69 are alternately actuated by co-operation of rollers 76 and 77 at their inner ends with oppositely inclined beveled surfaces 78 and 79 of a cam piece 80 on a longitudinally reciprocative rod 81. Springs indicated at 82 and 83 are influential upon the slides 68, 69 to keep the rollers 76, 77 thereon yieldingly engaged with the cam piece 80.

From Fig. 1 it will be noted that one end of the rod 81 is connected by means of a bracket arm 82, to an endwise reciprocated friction box rod or bar 83 of the machine, and from Figs. 2 and 4, that the outer end the cam piece 80 bears against a guide roller 84 supported by an extension 85a of the bottom plate 85 of block 70. Activity of the pawls 60, 61 and 62, 63 is controlled by a mechanism including guards or shields 86, 87 (Fig. 2) which are pivoted on the spindles 45 and 46 and adapted to be engaged respectively by studs 60a, 61a, and 62a, 63a, projecting laterally from said pawls. Through drop links 88, 89, the shields 86, 87 are connected to the horizontal arms of bell cranks 90, 91 independently fulcrumed in upstanding ears 92, 93 on the block 70. The upright arms of the bell cranks 90, 91 are in turn coupled, by means of separate link rods 94 and 95, with levers 96 and 97 respectively free between collars 98 on a horizontal rod 99. As shown, the levers 96 and 97 have finger projections 96a and 97a in the path of peripheral lugs 75

100a and 101a on rotary cams 100 and 101 which are fixed upon a longitudinally extending timing shaft 102 in the rear upper part of the machine. Through suitable mechanism (not illustrated) 5 the shaft 102 is turned stepwise through a complete revolution for each stocking knitting cycle of the machine. Springs, such as the one indicated at 103 in Fig. 4, serve to yieldingly maintain the finger projections 96a and 97a of the levers 96 and 97 in engagement with the rotary cams 100 and 101.

At certain times during the knitting of the heel cheeks of the stockings, the pawl shields 86 and 87 are moved to a neutral position as instanced in Fig. 6 by action of fingers 105, 106 (Figs. 1 and 4) upon the levers 96 and 97, said fingers being fixed upon a shaft 107 which is rockable in bearing bracket arms 108 supported by rod 83. Shaft 107 is actuated from the control mechanism of the machine through the medium of interposed parts, including an arm 110 (Figs. 1 and 3) on said shaft which, by means of a drop link 111 is connected to a similar arm 112 on a longitudinal rock shaft 113 in the lower rear portion of the machine. Also fast on the shaft 113 is a second arm 115 which, by means of vertical link 116, is connected to a horizontal arm 117 on a transverse shaft 118. As shown, this transverse shaft 118 has rotative support in bearing brackets 119 and 120 respectively on the rear and front bottom rails 25 and 121 of the machine framework. A pendent arm 122 (Figs. 1 and 7) on shaft 118 is in turn connected by an angular link rod 123 to the vertical arm of a bell crank 125 lever 125 free on another transverse shaft 126 with its horizontal arm in the path of a series of actuating buttons or lugs 127 on a timing chain 128 of the machine. As shown, the chain 128 is trained about a drive sprocket 129 free on a stud shaft 130 in a fixed bracket 131. The sprocket 129 is intermittently rotated to progress the chain 128 in the direction indicated by the arrow head thereon in Figs. 7 and 9, by means which includes a rotary cam 132 (Figs. 8 and 9) on the cam shaft 29 arranged to act upon a roller 133 on the upward arm of a bell crank 135 fulcrumed at 136 on an inward projection 137 of the bracket 131. A drop link 138 connects the horizontal arm of the bell crank 135 to an arm 139 (Fig. 7) which is free on the stud 130 and carries a pawl 140 for picking a ratchet wheel 141 affixed to the sprocket 129. The roller 133 on the bell crank 135 is shiftable into and out of the range of the rotary cam 132 through the medium of a fork 142 which is affixed to a spring-biased horizontal slide rod 143, the shifting being controlled by a rotary cam 145 on a supplemental longitudinal timing shaft 146 at the front of the machine near the bottom thereof. As shown, the cam 145 has a circumferential rise 147 adapted to underpass a finger 148 on a rock shaft 149, said finger having a lift arm 150 to engage beneath a horizontal shoulder 151 adjacent the boss of another finger 152 fulcrumed at 153 and bearing against a projection 155 on the boss of the fork 142. This arrangement, it will be seen, is such that the chain 128 will be progressed as long as the projection 147 of cam 145 remains beneath the finger 148 as is the case while the heel cheeks of a stocking is being knitted. Like the timing shaft 102 previously referred to, the auxiliary timing shaft 146 is turned through a complete revolution during each stocking knitting cycle of the machine.

Rod 83 (Fig. 2) is connected to a longitudinal

slide bar 165 by guide brackets whereof one is indicated at 166. Mounted on this slide bar is a friction box 167 with upstanding beveled ended ridges 168 and 169 whereof the frontal one has a notch 170 which is adapted to be engaged by a finger 171 pivoted at 172 between a pair of forward projections 173a of a slide boss or collar 173 on the rod 83, said collar also having a clevised projection 173b engaged between a pair of collars 174 affixed to the rod 81, see Figs. 2 and 3. The finger 171 has a rearward tail 171a which underreaches a rod 175 connected between the ends of a pair of spaced arms 176 on the shaft 99. Also affixed to the shaft 99 is a finger 177 adapted to be actuated by a peripheral projection 178a of another rotary disk cam 178 upon the timing shaft 102. By pull of a spring 179 (Fig. 3) upon one of the arms 176, the finger 177 is yieldingly held to the cam 178. Another spring at 180 tends to keep the tail 171a of said finger in operative contact with the rod 175.

In order to variably limit the inward traverse of the carriers 40 and 41 during heel cheek formation to correspond with the shifts of the presser blades 15 and 16, I have devised mechanism including a divided screw spindle with axially aligned oppositely-threaded end sections 185 and 186 (Figs. 1, 8, 9 and 11) which are engaged by follower nuts 187 and 188 respectively. Slidable endwise in the nuts 187 and 188 are stop bars 189 and 190 (Figs. 1, 10 and 11) adapted to be contacted respectively by adjustable stops 42a and 43a on the carrier bars 42 and 43. During formation of the parts other than the heel cheeks, the abutment bars 189 and 190 are held retracted within the nuts 187 and 188 as shown in Fig. 10. Thrust of the bars 189 and 190 to active position to intercept the carrier rods 42 and 43 is controlled from the timing shaft 102 which, for this purpose, is provided with two additional rotary cams 191 and 192 having circumferential rises 193 and 194 which are adapted to rock fingers 195 and 196 fulcrumed respectively at 197 and 198 on the nuts 187 and 188. By means of short links 199 and 200, the tails of the fingers 195 and 196 are coupled with fork arms 201 and 202 which are pivoted at 203 and 204 on the nuts 187 and 188, and which have cleised ends engaging lateral studs 205 and 206 at the upper ends of the stop bars 189 and 190. The fingers 195 and 196 are yieldingly maintained in contact with the cams 191 and 192 through exertion of a downward pull upon the bars 189 and 190 by individual springs indicated at 207 and 208. Secured to the spindle sections 185 and 186 adjacent opposite sides of a bearing 210 in which their contiguous inner ends are journalled, are ratchet wheels 211, 212 and 213, 214 with oppositely pitched teeth. Arranged to act upon the ratchet wheels 211, 212, 213, and 214 are pawls 215, 216 and 217, 218 which are pivoted for independent movement respectively on the opposite projecting ends of a pin 219 extending between the contiguous ends of two similar levers 220 fulcrumed on a horizontal shaft 221 at the top of the machine. The other ends of the levers 220 are connected, by means of a link rod 222 (Fig. 8), to the rear arm 223a of a lever 223 free on a shaft 225 clamped in fixed brackets 226 on the rear bottom rail 35 of the machine. The other arm 223b of lever 223 carries a roller 227 which is arranged to be acted upon by the rotary cam 132 on cam shaft 29 hereinbefore described. The roller 227 is shiftable into and out of the range of cam 132 by a fork 228 on a longitudinally extending rod 229 with guidance for endwise move-

ment in arms 230 clamped to the shaft 225. The rod 229 is shifted by means of an upright lever 231 at the inner end of a transverse rock shaft 232 rotatively supported in a downward projection 233 of the bracket 226 and in the bracket 131 on the rail 35 of the machine frame work. To the front end of the shaft 232 is affixed a finger 235 (Fig. 9) which overlies the sprocket 129 and which is arranged to be actuated by cam lugs 236 on the chain 128. As shown, a spring 237 in tension between the arms 135 and 223 tends to urge the rollers 133 and 227 toward the cam 132. Selectivity as between the pawls 215, 216 and 217, 218 to determine intermittent rotation of the spindle sections 185 and 186 in opposite directions, is effected by means of shield elements 240 and 241 which are independently movable about said spindle sections and adapted to contact the inner sides of said pawls. By means of link rods 242 and 243, the shield elements 240 and 241 are respectively coupled with the upright arms of bell cranks 245 and 246 individually free on the shaft 247. The short lateral arms of the bell cranks 245 and 246 are in turn connected, by link rods 248 and 249 (Figs. 7 and 9), with arms 250 and 251 respectively on the rear ends of transversely extending rock shafts 126 and 253 which are rotatively supported in the downward extension 233 of the bracket 226 on the rear bar 35 of the machine framework and in the bracket 131 on the front bar 121. The forward ends of the shafts 126 and 253 are secured fingers 255 and 256 which overreach the sprocket 125 and which are adapted to be actuated by cam lugs 257 and 258 on the chain 128.

Operation

A stocking blank is knitted on each section of the machine down through the leg in the usual way, with incidental fashioning by narrowing of the web inwardly from the opposite selvages. During the leg knitting, the following normal conditions obtain in the machine: The finger 171 (Figs. 1 and 2) is held withdrawn from the friction box 167, with the selector blade shifting screw spindles 45 and 46 idle, and with the follower nuts 50 and 51 positioned on said spindles as shown in broken lines in Fig. 2; the levers 96 and 97 are engaged with the concentric portions of the rotary cams 100, 101 on the upper timing shaft 102 as shown in full lines in Fig. 4, with the shields 86 and 87 positioned as in Fig. 6 and the pawls 60 and 61 ready to operate on the ratchet wheels 55 and 57; and the finger 148 rests upon the concentric portion of rotary cam 145 on the lower timing shaft 148 (Fig. 8), with the roller 143 on arm 142 out of the range of cam 132 on main cam shaft 29 and the control chain 128 quiescent, and with the stops 189 and 190 retracted as in Fig. 10 so that one of the yarn carriers 40, 41 may be transversed to the fullest extent in the leg knitting.

For explanation of the heel knitting, reference will be had from time to time to diagrammatic Figures 14-22, wherein the needles N are represented by a series of small circles which are numbered outwardly in opposite directions from the center of the needle bar 21. When the knitting has proceeded to the course at which the heel cheeks are to be begun, the press movement of the needle bar 21 is modified as in my patent hereinbefore referred to, to prevent contact of the beards of the needles, except for those of the end groups selected by the blades 15 and 16, with the presser edge indicated at 260 in Figs. 2, 3 and 10 on the sinker head of the machine. At

the start of the heel knitting, the selector blades 15, 16 and the yarn carriers 40, 41 are positioned relative to the needles as shown in Fig. 14. The heel knitting is initiated by concurrent partial turns of the upper and lower timing shafts 102 and 146. By the rotative shift of the upper timing shaft 102, the rise 178a of the cam 178 thereon is moved into engagement with the finger 177 as in Fig. 3, for connection of the rod 81 to the friction box 167. Therefore, during the knitting of the upper heel gores, with the pawls 60 and 61 positioned as in Fig. 4 as previously explained, each time that the cam piece 80 moves to the right in Fig. 2, the slide 68 will be thrust forwardly and a tooth of the ratchet wheel 56 picked by the pawl 60 to rack the spindle 45. As a result, the follower nut 50 is moved leftward from the broken line position of Fig. 2 to shift the selector blade 15 in the same direction to the extent of two needles. On the other hand, each time that the cam piece 80 is moved to the left in Fig. 2, the slide 69 will be actuated with consequent picking of a tooth of the ratchet wheel 57 by the pawl 61 and racking of the spindle 46 in Fig. 4 to move the nut 51 rightward, whereby the selector blade 16, connected to said nut through the slide bar 39, will be shifted in the same direction, likewise by two needles. Also by the instant rotative shift of the timing shaft 102, the rises of cams 191 and 192 thereon are advanced beyond the fingers 195 and 196 as in Fig. 10, with the result that the abutment or stop bars 189 and 190 are projected from the follower nuts 187 and 188 on the screw spindles 185 and 186 into the path of the stop lugs 42a and 43a on the carrier bars 42 and 43. By the instant shift of the lower timing shaft 146, the rise 147 of cam 145 thereon is advanced beneath the finger 148 as in Fig. 8, whereby the roller 133 of arm 135 is moved to the range of rotary cam 132 on main cam shaft 29, and said arm actuated to start intermittent progression of the control chain 128. During the knitting of the narrowed upper heel cheek gores, the fingers 255 and 256 are actuated each time by a pair of lugs of the series 257 and 258 on control chain 128 underpasses them. As a consequence, through the intermediate connections previously described, the pawl shields 240, 241 are moved to the positions shown in Fig. 8, with incidental selection of the pawls 215 and 218 in readiness to pick the ratchets 211 and 213 and thereby concurrently rotate the spindles 185 and 186 to shift the nuts 187 and 188, together with the stops 189 and 190, outward each time by the distance of two needles. As the lugs of the series 127 on chain 128 successively underpass and actuate the finger 125, the pawl shields 86, 87 are moved to neutral position as in Fig. 6 for suspension in the racking of the selector blade shifting screw spindles 45 and 46 occasionally during the formation of the upper gores. The above described conditions hold throughout the formation of the upper heel gores. In the present instance the lugs 127, 257, and 258 are so arranged on the chain 128 that in the first, fifth and seventh courses of the heel knitting, the selector blade 16 is moved outward each time by two needles, while the selector blade 15 is moved outward by two needles in the second, fourth, eighth and tenth courses as will be more fully explained later. During the knitting of the lower heel gores, the lugs 236 on timing chain 128, in underpassing the lever 235, cause the pawl shields 240 and 241 to be displaced from the position in which they are shown in Fig. 8, so that the screw spindles 185 and 186 will then be re-

versely shifted to progressively move the carrier stops inwardly toward each other.

In preparation for the knitting of the lower heel gores, the upper automatic shaft 102 is given another rotative shift whereby the projections 100a and 101a of the cams 100 and 101 are brought into play to actuate the levers 96 and 97 for displacement of the shields 86 and 87 as in Fig. 5, to withdraw the pawls 60, 61 and allow the pawls 62, 63 to assume active positions. As a consequence, the screw spindles 45 and 46 will thereafter be reversely rotated to progressively move the selector blades 15, 16 inwardly toward each other alternately and respectively in every other course of the lower gore knitting. The heel knitting is terminated through stoppage of the timing chain 128 which is brought about by another rotative shift of the lower automatic shaft 146 for movement of the projection 147 (Fig. 8) of cam 145 from beneath the finger 148. By a concurrent additional rotative shift of the upper timing shaft 102 (Figs. 10 and 11), the projections of cams 191, 192 will be moved into engagement with the fingers 195 and 196 for retraction of the yarn carrier stops 189 and 190. By the same rotative shift of the upper timing shaft 102 (Fig. 3), the lug 178a on cam 178 will be moved past the arm 177 to withdraw of the finger 171 from the friction box 166 with consequent idling of the racking mechanism for the selector blade shifting spindles 45 and 46. With the immediately foregoing accomplished, the machine will be restored to the normal condition for completion of the foot portion of the stocking.

In the commercial production of stockings with my improved machine, the number of courses employed in the upper and lower heel gores respectively may be in the ratio of three to two. It therefore follows that if a hundred and fifty courses in all are employed for example, ninety of them will be assigned to the narrowed upper gores A—B—E and C—D—F in Fig. 12, and sixty of them to the complementary widened lower gores B—E—G, C—F—H. The upper gores result from repetition of a cycle of which the successive steps are illustrated in Figs. 14—22 as determined by the arrangement of the lugs 127, 257, and 258 on the control chain 128. Fig. 14 shows the selector blades 15 and 16 and the yarn carriers 40, 41 in the positions which they occupy at the start of the heel knitting. During formation of the first course of each upper gore, the selector blade 16 alone is moved outward by two needles and the inner yarn carrier stops 189, 190 concurrently moved outward each by two needles, so that, at the completion of this course, after leftward traverse of the carriers 40, 41 in Fig. 15 the respective heel yarns are fed to the needles 6—16 of the lefthand heel group and to the needles 8—16 of the right hand heel group. During the formation of the second course of each upper gore as in Fig. 16, the selector blade 15 alone is moved outward by two needles without change in the position of the carrier stops 189, 190, so that at the completion of this course, after leftward traverse of the carriers 40, 41, the respective heel yarns are fed to the needles 8—16 of the left hand heel group and to the needles 8—16 (again as in Fig. 15) of the right hand heel group. In the third course (Fig. 17) neither the selector blades 15, 16 nor the carrier stops 189, 190 are shifted, so that the respective heel yarns are once more fed to the needles 8—16 of both heel groups as in the second course (Fig. 16) by rightward traverse of the carriers 40, 41. During the formation of the fourth course (Fig. 18), the selector blade

15 alone is moved outward by two needles and the inner yarn carrier stops 189, 193 concurrently moved outward each by the same amount, so that at the completion of this course after rightward traverse of the carriers, the respective heel yarns are fed to the needles 10—16 of the left hand heel group and to the needles 8—16 (again as in Figs. 16 and 17) of the right hand heel group. During the formation of the fifth course, the right hand selector blade 16 alone is moved outward by two needles without change in the position of the carrier stops 189, 193 so that at the end of this course, after leftward traverse of the carriers as in Fig. 19, the respective heel yarns are fed to the needles 10—16 of 15 the left hand heel group (again as in Fig. 18) and to the needles 18—16 of the right hand heel group. The sixth course, Fig. 20, is completed without change in the position either of the selector blades 15, 16 or of the carrier stops 189, 193, so that with the respective heel yarns are fed to the needles 10—16 of both heel groups (as in Fig. 19) after traverse of the carriers to the right. Thus during the upper gore formation, the selector blade 16 is moved outwardly in the first course, 25 remains quiescent in the third course, is moved outwardly in the fifth and seventh courses, remains quiescent in the ninth course etc.; while the left selector blade 15 is moved outwardly in the second and fourth courses, remains quiescent 20 in the sixth course, is moved outwardly in the eighth and tenth courses etc. This order being continuously repeated until the ninetieth course of the knitting is reached. As a consequence, the upper heel gores will be narrowed by two 35 needles each time from opposite sides of the stocking blanks at variant intervals i. e., at every second and fourth course in alternation as instanced in the lower portion of Fig. 13. At the start of the lower heel gores in the ninety-first course (Fig. 21), the selector blade 16 alone is moved inward to the extent of two needles and the carrier stops 189, 193 concurrently moved inward each by the same amount as the carriers 40 are traversed to the left, and the respective heel yarns fed to the needles 10—16 of the left hand heel group and to the needles 8—16 of the right hand heel group. In the ninety-second course of the knitting, which is shown completed in Fig. 22, the selector blade 15 alone is moved inward to the extent of two needles and the carrier stops 189, 193 are moved inwardly concurrently each by a like amount, as the respective heel yarns are fed to the needles 8—16 of both groups. The latter procedure is repeated over and over again until the one hundred and fiftieth or terminal course is reached, whereby the lower heel gores are narrowed by two needles each time from opposite edges of the stocking blank at regular intervals, i. e., in every other course of the knitting as instanced in the upper portion of Fig. 13. Thus, as will be readily understood, the vertical elongate configuration of the heel cheeks is therefore due to shifting of the selector blades 15, 16 and carrier stops 189, 193 at differently spaced intervals during the knitting of the upper heel gores, and to shifting of said blades and stops at regular intervals during the widening of the lower heel gores, with the use of a greater number of courses in the narrowing than in the widening.

Having thus described my invention, I claim:

1. In a straight knitting machine, a series of spring beard needles, a friction box bar with a friction box mounted thereon; blade-like selectors for flexing selected needles of two groups

respectively at opposite ends of the series to bring their beards into contact with a presser edge in stitch formation; means for oppositely shifting the needle selectors along the needles including right and left hand threaded screw spindles, follower nuts on the spindles respectively connected to the selectors, pairs of oppositely-pitched ratchet wheels on the respective spindles, two sets of pawls for picking the respective ratchets on the corresponding spindles, a pair of transversely arranged slides carrying the respective sets of pawls, a rod supported for longitudinal reciprocation adjacent the friction bar, a cam on the rod operative as the latter moves in opposite directions to alternately actuate the slides, and coupling means for releasably connecting the rod to the friction box; and control mechanism for actuating the coupling means to operate the selector shifting means, and for selecting corresponding pawls of the two sets for activity during one knitting phase and the other pawls for activity during the other knitting phase.

2. A straight knitting machine according to claim 1, wherein the selector shifting mechanism further comprises means for selecting between the corresponding pawls of the two sets; and wherein the control mechanism controls the pawl selecting means to determine rotation of the screw spindles in one direction during one knitting phase and in the opposite direction during the other knitting phase.

3. A straight knitting machine according to claim 1, wherein the selector shifting mechanism further includes means for selecting between corresponding pawls of the two sets; wherein the control mechanism controls the pawl selecting means to determine rotation of the screw spindles in one direction during one knitting phase and in the opposite direction during the other knitting phase; and further including means also controlled by the control mechanism for determining operation of one set of pawls at irregular intervals during one of the knitting phases.

4. In a straight knitting machine, a row of spring beard needles; a selector adapted to act upon selected needles and cause their beards to be closed in stitch formation; means for progressively shifting the selector along the needles in one direction during a certain phase of the knitting and in the opposite direction during another phase of the knitting, including a screw spindle, a follower nut on the spindle connected to the selector, oppositely pitched ratchet wheels on the spindle, separate pawls for picking the respective ratchets, and a movable guard for selecting between the pawls for operation during the respective knitting phases; timing means for actuating the guard to permit one pawl to function during one knitting phase, and the other pawl to function during the other knitting phase; and control means for moving the guard to a neutral position to prevent functioning of both pawls at different prescribed intervals during the respective knitting phases.

5. In a straight knitting machine, a row of spring beard needles; selectors adapted to act upon selected needles of two groups of needles respectively at opposite ends of the series and cause their beards to be closed in stitch formation; means for progressively shifting the selectors toward each other along the needles during a certain phase of the knitting and away from each other during another phase of the knitting, including right and left hand screw spindles, follower nuts on the spindles whereto the selectors

are respectively connected, pairs of oppositely pitched ratchet wheels on the respective spindles, two sets of pawls for picking the respective ratchets on the spindles, and a movable guard associated with each pair of the pawls for selecting between the two pawls for individual activity during the respective knitting phases; timing means for actuating the guards to permit corresponding pawls of the two pairs to function during one knitting phase and the other pawls to function during the other knitting phase; and control means for moving the guards to neutral position to prevent functioning of the pawls at different prescribed times during the respective knitting phases.

6. In a straight knitting machine, a reciprocating friction box bar; a row of spring beard needles; a selector for acting upon selected needles and causing their beards to be closed in stitch formation; means for shifting the selector along the needles including a screw spindle and a follower nut on the spindle connected to the selector; reversible racking means for the spindle; connections through which the racking means is actuated from the friction box bar; and control means for controlling the racking means to rotatively shift the spindle in one direction during a certain phase of the knitting and in the other direction during another phase of the knitting.

7. A straight knitting machine according to claim 6, wherein the control mechanism causes shifting of the needle selector at regular intervals during one knitting phase, and at different intervals during the other knitting phase.

8. In a straight knitting machine, a reciprocating friction box bar; a row of spring beard needles; selectors for acting upon selected needles of two groups at opposite ends of the series to cause their beards to be closed in stitch formation; carriers for feeding yarns to the respective needle groups; means for oppositely shifting the selectors along the two needle groups including right and left hand screw spindles and follower nuts on the spindles whereto the selectors are respectively connected; reversible racking means for the individual spindles; connections through which the racking means is actuated from the friction box bar; and control means for controlling the racking means to cause rotative shifts of the spindles in one direction during a certain phase of the knitting and in the other direction during another phase of the knitting.

9. A straight knitting machine according to claim 8, wherein the control mechanism causes shifting of the needle selectors at regular intervals during one knitting phase, and at different intervals during the other knitting phase.

10. In a straight knitting machine, a row of spring beard needles; selectors adapted to act upon selected needles of two groups respectively at opposite ends of the series and cause their beards to be closed in stitch formation; means for oppositely shifting the selectors along the needles including right and left hand threaded screw spindles; follower nuts on the spindles respectively connected to the selectors; reversible racking means for rotatively shifting the spindles in one direction during one phase of the knitting and in the other direction during another phase of the knitting; a longitudinally reciprocating rod; and connections through which the racking means for the screw spindles is actuated from said rod.

11. In a straight knitting machine, a row of spring beard needles; selectors adapted to act

upon selected needles of two groups respectively at opposite ends of the series and cause their beards to be closed in stitch formation; means for oppositely shifting the selectors along the needles including right and left hand threaded screw spindles; follower nuts on the spindles respectively connected to the selectors; reversible racking means for rotatively shifting the spindles in one direction during one phase of the knitting, and in the other direction during another phase of the knitting; a friction box bar with a friction box mounted thereon; a slide rod extending parallel to the friction box bar; connections through which the spindle racking mechanism is actuated from the rod; and means controlled by the control mechanism for releasably coupling the rod to the friction box.

12. In a straight knitting machine, a row of spring beard needles; selectors adapted to act upon selected needles of two groups respectively at opposite ends of the series and cause their beards to be closed in stitch formation; means for oppositely shifting the selectors along the needles including right and left hand threaded screw spindles; follower nuts on the spindles respectively connected to the selectors; reversible racking means for rotatively shifting the spindles in one direction during one phase of the knitting and in the other direction during another phase of the knitting, said racking means comprising pairs of oppositely pitched ratchet wheels on the respective spindles, two sets of pawls for picking the ratchet wheels on the corresponding spindles, a pair of transversely arranged slides carrying the respective sets of pawls, and a reciprocated cam operative by movement in opposite directions to alternately actuate the slides; and means controlled by the control mechanism and operative to select corresponding pawls of the two sets for activity during the one phase of the knitting, and the other pawls of said sets for activity during the other phase of the knitting.

13. In a straight knitting machine, a row of spring beard needles; a selector adapted to act upon selected needles and cause their beards to be closed in stitch formation; means for progressively shifting the selector along the needles in one direction during a certain phase of the knitting and in the opposite direction during another phase of the knitting, including a screw spindle, a follower nut on the spindle connected to the selector, oppositely-pitched ratchet wheels on the spindle, separate pawls for picking the respective ratchets, and means for selecting between the pawls for operation during the respective knitting phases; timing means for actuating the selecting means to permit one pawl to function during one knitting phase and the other pawl to function during the other knitting phase; and separate control mechanism for controlling the selecting means to prevent functioning of both pawls at prescribed intervals during the respective knitting phases.

14. In a straight knitting machine, a row of spring beard needles; selectors adapted to act upon selected needles of two groups of needles respectively at opposite ends of the series and cause their beards to be closed in stitch formation; means for progressively shifting the selectors toward each other along the needles during a certain phase of the knitting and away from each other during another phase of the knitting, including right and left hand screw spindles, follower nuts on the spindles whereto the selectors are respectively connected, pairs of oppositely

pitched ratchet wheels on the respective spindles, two sets of pawls for picking the respective ratchets on the spindles, and means for selecting between the pawls of the respective pairs for individual activity during the respective knitting phases; timing means for actuating the selecting means to permit corresponding pawls of the two pairs to function during one knitting phase and the other pawls to function during the other knitting phase; and separate control mechanism for controlling the selecting means to prevent functioning of all the pawls during different prescribed times during the respective knitting phases.
